UNITED STATES PATENT OFFICE.

BYRON W. HASTINGS AND CHARLES W. KELLEY, OF McCOOK, NEBRASKA.

CYLINDER-HEAD LIFTER.

Application filed September 13, 1927. Serial No. 219,310.

This invention relates to a cylinder head lifter, and it is an object of the invention to provide a device of this kind for facilitating the removal, handling and reinstalling 5 of cylinder heads for internal combustion engines without removing the rocker arms and shafts.

It is also an object of the invention to provide a device of this kind to facilitate 10 easier handling of cylinder heads and to speed up service operation by permitting a cylinder head to be removed, handled and reinstalled while assembled.

An additional object of the invention is 15 to provide a lifter of this kind which operates to hold the rocker arms in their natural operating position while handling a head and which in its use avoids the necessity of removing bolts, rocker arms, rocker arm 20 shafts and studs from the cylinder head.

Furthermore, it is an object of the invention to provide a device of this kind which permits the handling of a cylinder head while hot and which can be readily 25 used by one man with one hand free to line up push rods.

The invention also has for an object to provide a lifter of this kind which can be readily employed for properly manipulating 30 a cylinder head without danger of spilling oil or sediment from the valve pockets.

The invention consists in the details of 35 construction and in the combination and arrangement of the several parts of our improved cylinder head lifter whereby certain important advantages are attained and the device rendered simpler, less expensive and otherwise more convenient and advantageous for use, as will be hereinafter more fully 40 set forth.

The novel features of our invention will hereinafter be definitely claimed.

In order that our invention may be the better understood, we will now proceed to 45 describe the same with reference to the accompanying drawings, wherein:—

Figure 1 is an elevational view of a cylinder head with a lifter constructed in accordance with an embodiment of our invention 50 operatively engaged therewith;

Figure 2 is a view in top plan of the structure as illustrated in Figure 1;

Figure 3 is a view in end elevation of the structure as shown in Figure 1 with the 55 major portion of the cylinder head and its

parts diagrammatically indicated by broken lines;

Figure 4 is a view in perspective of our improved lifter as herein disclosed unapplied.

As disclosed in the accompanying drawings, H denotes a cylinder head of a well known type provided with overhead valves. Each of the valves comprises an upstanding stem 1 constantly urged outwardly by an encircling spring 2 and which has contact in a well known manner with an end portion of a rocker arm 3 supported substantially midway its length upon a rocker shaft 4. The shaft 4 is operatively mounted upon the head H in spaced relation thereto through the medium of a bearing block 5 or the like.

Our improved lifter, as herein disclosed, comprises a substantially U-shaped member M, the side members 6 of which have their free extremities continued by the substantially perpendicularly related fingers 7 arranged in parallelism. Each of these extensions or fingers 7, as herein disclosed, is substantially sigmoidal in form with the inner part of its upper marginal portion recessed, as at 8, so that said fingers 7 may be readily engaged beneath the shafts 4 and effectively engage the same when it is desired to lift the head H.

Pivots connected, as at 9, with the side members 6 of the member M are the side members 10 of a second substantially U-shaped member M'. The pivotal connections 9 are positioned a material distance inwardly of the free extremities of the side members 10 of the member M'. Disposed through and supported by said free extremities of the side members 10 is an elongated rod 11 which extends a material distance beyond the opposite ends of the member M.

When it is desired to lift or otherwise handle a cylinder head, the fingers 7 are engaged from below or inwardly of the shafts 4 and the intermediate portion of the member M' is swung toward the intermediate portion of the member M. This movement of the member M' will bring the rod 11 into contact with the end portions of the rocker arms 3 contacting with the valve stems 1.

The members M and M' when in working engagement with the head H have their intermediate portions sufficiently close to

gether to permit the same to be readily grasped by one hand of the operator leaving the other hand free to line up the push rods or to perform such other necessary 5 operations as may be required.

It is also believed to be obvious that with the use of our improved lifter as herein set forth it eliminates the necessity of removing bolts, rocker arms, rocker arm shafts 10 and studs from a cylinder head when being removed, handled or reinstalled and that the lifter holds the rocker arms during such manipulations in their natural operating positions. It will be understood that the construction of our lifter is such that the 15 tighter the members M and M' are held the harder the device will grip the head.

From the foregoing description it is thought to be obvious that a cylinder head 20 lifter constructed in accordance with my invention is particularly well adapted for use by reason of the convenience and facility with which it may be assembled and operated, and it will also be obvious that our 25 invention is susceptible of some change and modification without departing from the principles and spirit thereof and for this reason we do not wish to be understood as limiting ourselves to the precise arrangement and formation of the several parts 30 herein shown in carrying out our invention in practice except as hereinafter claimed.

We claim:

1. A cylinder head lifter comprising a

U-shaped member, the side members of 35 which have their free extremities provided with angularly disposed fingers, a second U-shaped member having its side members pivotally engaged with the side members of the first named U-shaped member, and a 40 rod carried by the free extremities of the side members of the second U-shaped member.

2. A cylinder head lifter comprising a 45 U-shaped member, the side members of which have their free extremities provided with angularly disposed fingers, a second U-shaped member having its side members pivotally engaged with the side members of the first named U-shaped member, and a 50 rod carried by the free extremities of the side members of the second U-shaped member and extending beyond the opposite ends of the first named U-shaped member.

3. A cylinder head lifter comprising two 55 pivotally connected members, one of said members having means to engage from below the rocker arm shafts of a cylinder head, the other of said members having means to engage the rocker arms carried by the head for holding said rocker arms in substantially their normal positions during a lifting operation.

In testimony whereof we hereunto affix our signatures.

BYRON W. HASTINGS.
CHARLES W. KELLEY.
